CLAIM

The ornamental design for a hub seal, as shown and described.

DESCRIPTION

Portions of the disclosure of this patent document contain material that is subject to copyright protection. The copyright owner has no objection to the facsimile reproduction by anyone of the patent document or the patent disclosure, as it appears in the U.S. Patent and Trademark Office patent file or records, but otherwise reserves all copyright rights whatsoever.

FIG. 1 is a perspective view of an exemplary embodiment of a new and novel ornamental design for a hub seal and cover. FIG. 2 is a view from the front of the perspective view of the embodiment of the design shown in FIG. 1.

FIG. 3 is a cross-sectional view of the design shown in FIG. 2 along section cut B-B; and,

FIG. 4 is a view from the side of the perspective view of the embodiment of the design shown in FIG. 1.

The design is a hub seal and cover that fits integrally on for example, an airplane wheel hub.
